(57) **CLAIM**

The ornamental design for jewelry article with two interlocking links, as shown and described.

DESCRIPTION

FIG. 1 is a top and front isometric view of a jewelry article with two interlocking links showing my new design;
FIG. 2 is a top view thereof;
FIG. 3 is a bottom view thereof;
FIG. 4 is a left side view thereof;
FIG. 5 is a right side view thereof;
FIG. 6 is a front view thereof; and,
FIG. 7 is a back view thereof.

The broken lines shown in FIGS. 1-5 and 7 represent portions of the jewelry article with two interlocking links which form no part of the claimed design.
